SKIVING MACHINE

Hiotte A. Davis, Lynchburg, Va., assignor to
 United Shoe Machinery Corporation, Paterson,
 N. J., a corporation of New Jersey

Application June 27, 1933, Serial No. 677,883
 Renewed August 13, 1935

6 Claims. (Cl. 69—16)

This invention relates to skiving machines and is herein illustrated as embodied in a machine of the well-known Amazeen type for skiving the edges of pieces of upper leather.

- 5 In the manufacture of certain kinds of shoes it is desired to produce on a single part of an upper two or more scarfs which are different in width or in character, or in both. For example, it may be necessary to provide along the top and 10 front of a quarter a shoulder or fold scarf, to produce along the bottom a feather edge or underlap scarf and to produce along the back a seam scarf. In such and similar cases, it is desirable that the operator be able instantly to change the 15 relative positions of the work-engaging parts of the machine so as to avoid delay in producing first one kind of scarf and then another, said work-engaging parts commonly comprising a knife, a feed roll, a presser and an edge guide.
- 20 To this end, in accordance with one feature of the invention, the edge guide is adjustable across the periphery of an angularly adjustable feed roll and is yieldingly held at one limit of its path of adjustment, operator-controlled means being 25 provided for instantly moving it to another position. In the illustrated machine, the feed roll is mounted upon a carrier which may be angularly adjusted by means of a treadle, the edge guide is slidably mounted on the feed roll carrier 30 so as to be angularly adjustable with it, and a second treadle connected to the edge guide provides means for adjusting the guide across the periphery of the roll. With such a construction, the relative positions of the work-engaging parts 35 may be changed instantly in various ways by manipulating one or both treadles to produce a variety of scarfs one after another in any desired order.

This and other features of the invention including certain details of construction and combinations of parts will be described as embodied in an illustrated machine and pointed out in the appended claims.

Referring now to the accompanying drawings 45 Fig. 1 is a front elevation of a machine in which the present invention is embodied,

Fig. 2 is a horizontal section on the line II—II of Figs. 1 and 3;

Fig. 3 is a vertical section on the line III—III 50 of Fig. 4;

Fig. 4 is a vertical section on the line IV—IV of Fig. 2;

Figs. 5 to 9^a show certain parts of the machine in different positions of adjustment and 55 certain kinds of scarfs which are produced.

The illustrated machine is similar in many respects to the machine disclosed in United States Letters Patent No. 1,866,918, granted June 12, 1932, upon an application filed in the name of Milton H. Ballard. The present machine, like 5 that of the patent, comprises a rotary disk knife 9, a rotary feed roll 11, and a rotary feed disk 13. The knife is adjustable substantially vertically toward and from the feed roll. The feed disk presses a portion of the work against a reduced 10 end of the feed roll and aids in feeding the work. The feed roll shaft is rotatable in a block 15 which is adjustable substantially horizontally in a support 17, said support being angularly adjustable in a curved guideway the center of curvature of 15 which lies in a horizontal axis indicated at x which passes through an element on the upper surface of the feed roll. It will be noted, however, that by adjusting the block 15 to the right or left, the position of the point x on the periphery of the feed roll may be changed. The block 15 carries a superstructure by which the feed disk is carried so that angular adjustment of the feed roll support 17 about the axis x adjusts the feed disk. The feed disk and feed roll thus 20 preserve at all times their relative positions. The curved guideway in which the feed roll support is adjusted is located at the outer end of a large arm 19, said arm being angularly adjustable in a horizontal path about the axis of a vertical 25 stud 21 to adjust the feed roll toward and from the knife; and the feed roll shaft is connected by a telescoping shaft 23 and universal joints with a driving pulley 25. The feed roll support 17 is connected by a link 27 with a treadle controlled arm 29 pivoted at 31 and carrying a small block 33. Two small adjusting nuts 35, threaded on a small rod 37, limit the rocking movement of the arm 29 and hence the extent of angular adjustment of the feed roll support 17. The arm 29 30 is connected by a link 30 and a pivot 32 with the upper end of a treadle rod 39 in such manner that vertical movement of the rod swings the arm to the right or the left. The lower end of the rod is connected to a treadle 41 normally held 40 with its toe portion up by a spring 40 to hold the feed roll 11 in its up position in which the uppermost element of its periphery is parallel to the plane of the knife 9 or substantially so. An edge guide 43 which is carried indirectly by the block 45 45 15 has a stem 45 which carries a yieldingly-mounted adjustable presser 46. The machine, as thus far described, is or may be substantially the same as the patented machine and will not be described further in detail. It will be noted, 50 55

however, that the work to be skived is fed away from the observer, as viewed in Fig. 1, with its edge against the guide 43 and its margin beneath the presser, to the rotary knife 9. With the parts 5 in their normal position, as shown in Fig. 1, a shoulder or fold scarf (to be described later) will be produced; and when the treadle is depressed to swing the roll down in a counterclockwise direction until the small block 33 encounters 10 the right hand stop 35, a feather edge scarf will be produced, the positions in which the two limiting stops 35 are held thus determining the characteristics of the two scarfs.

The edge guide and presser, except for a means 15 for quickly adjusting them in a path parallel to the axis of the roll shaft, are or may be substantially like the guide and presser disclosed in United States Letters Patent No. 1,829,792, granted November 3, 1931, to Newell V. Dyer. The presser 46 20 (Fig. 4) is fast to the outer end of a three-part spring 47 of elongated U-shape, the ends of which are fastened by a screw 49 and spacers 51 to the stem 45 of the edge guide. A thumb screw 53 may be turned to raise and lower the presser, and a 25 thumb nut 55 may be turned to vary the force which the presser exerts upon the work.

In the present construction the guide and presser, instead of being adjustable horizontally by hand and held fast in adjusted position, may 30 be moved instantly from one horizontal position to another by a treadle, adjustable stops being provided for limiting the extent of this movement. The stem 45 of the guide 43 is slidably mounted in a bracket 57 (Figs. 1, 2 and 3) having a horizontal portion 57' (Figs. 2, 3 and 4). The upright portion of the bracket 57 (Fig. 1) has slots 59 to receive screws 61 the stems of which pass through these slots and are threaded into a block 63 which, like the corresponding block of the machine of 35 Patent No. 1,866,918, is angularly adjustable and may be locked in adjusted position. Referring now more particularly to Figs. 2, 3 and 5, the stem 45 of the guide 43 is wider at its rear end (the right-hand end as viewed in Figs. 2 and 4) and 40 this widened portion rests upon the horizontal portion 57' of the bracket 57. One edge of this widened portion (the left-hand edge as shown in Fig. 3) is shaped to project into a guideway having an overhanging wall which is formed on the bracket 57. The opposite edge is beveled at an 45 abrupt angle, and the upper corner of this bevel is engaged by the beveled edge of a hardened plate 65 which is fastened by screws 67 to the upright portion of the bracket 57. The widened portion of the stem 45 is thus held in place and guided in its sliding movement. In order further to guide the stem 45, a guide-block 69 (Fig. 3) is located in an opening in the upright portion 50 of the bracket 57, said guide-block having a face which is slightly undercut to fit against the abruptly beveled edge of the stem 45 and being fastened to the horizontal portion 57' of the bracket 57 by a screw 71, there being a small space between the block 69 and the end of the horizontal portion 57' so that any wear on the surface of the block and the stem may be taken up by tightening the screw.

It is desirable, for reasons presently to be stated, 70 that means be provided for predetermining the limits of sliding movement of the guide and presser. To this end a U-shaped member 73 is fastened by screws 75 to the under side of the horizontal portion 57' of the bracket 57; and through the upwardly extending arms of this U-shaped member are threaded respectively stop

screws 77, 79 held respectively in adjusted position by check nuts 81, 83. The stop screws lie in the path of movement of the widened portion of the stem 45 of the edge guide and provide means for arresting the sliding movement of the guide 5 and presser in both directions.

In order to hold the stem of the guide normally against the stop screw 77 and to provide means for quickly moving the stem to the left (Fig. 4) toward or into contact with the stop screw 79, a 10 sheet metal bracket 85 (Figs. 2, 3) is fastened along one edge of the stem 45 by the same screw 49 which fastens the ends of the arms 41 of the horizontally disposed U-shaped spring which carries the presser 46, the outer edge of the sheet 15 metal bracket having a recess to receive the upper end of a shifting lever 87 which is pivoted to the frame of the machine about the stem of a screw 89 (Fig. 2). Referring to Fig. 1, the lower end of this lever 87 passes through a slot in the 20 top 91 of the bench upon which the machine is mounted and is urged continually to the left by a tension spring 93 so as to hold the widened portion of the stem 45 of the edge guide against the stop screw 77, the guide and presser being 25 then in their normal retracted positions. A treadle 95 provides means for swinging the lower end of the lever 87 to the right to move the guide and presser to the left until the widened portion of the stem 45 of the edge guide contacts with 30 the stop screw 79. This treadle is connected by a treadle rod 96 with an arm 97 the hub of which is fast to a rock-shaft 99. Also fast to this rock-shaft is the hub of a second arm 101 the outer end of which is connected by a link 103 with the 35 lower end of the shifting lever 87. With this construction, the feed roll 11, the guide 43 and the presser 46 normally occupy the positions shown in Fig. 1. The treadle 41 may be depressed at any time to tilt the feed roll whereupon the 40 guide and presser tilt with it; and the treadle 94 may be depressed at any time to slide the guide and presser to the left.

The purpose of this construction, as has been indicated above, is to provide for instantly adjusting these parts of the machine so that the operator may change rapidly from one kind of scarf to another. Referring now more particularly to Figs. 7 to 9a, some of the ways in which 45 different scarfs may be produced will be described. In Fig. 7, the parts are in the same position as they are shown in Fig. 1, the feed roll 11 being in its normal uppermost angular position and in its longitudinal position in which the axis about which it may be tilted passes through the 50 point x on the upper element of the roll, the guide 43 and the presser 46 being in their normal horizontal position with respect to the feed roll with the widened portion of the stem 45 held against the right end stop screw 77. With the machine 55 so adjusted, in which position of adjustment the upper element of the feed roll is parallel to the plane of the knife or substantially so and the work-engaging face of the edge guide is substantially in line with the right-hand face of the roll, 60 the shoulder or fold scarf of Fig. 7a will be produced. If now it is desired to produce a feather edge scarf shown in Fig. 8a, the treadle 41 is depressed to tilt the roll about the axis x into the position shown in Fig. 8 and also in Fig. 5. It 65 should be here noted that the fold scarf of Fig. 7a and the feather edge scarf of Fig. 8a are of substantially the same width. If now it is desired to produce the blunt edge seam scarf of Fig. 9a, the treadle 95 is depressed to slide the guide 70

43 and the presser 46 to the left until the left-hand stop screw 79 stops such movement, whereupon the parts will be in the positions shown in Fig. 9 and also in Fig. 6. It may be noted that 5 the seam scarf of Fig. 9^a is like the feather edge scarf of Fig. 8^a, except that its extreme end has been cut off.

It may sometimes be desired to produce a fold scarf which is narrower than the feather edge 10 scarf. In such case the feed roll is held in its normal uppermost position, as shown in Fig. 7, and the guide and presser are moved to the left 15 into the positions which they occupy in Fig. 9, so that the edge guide is over the periphery of the 20 roll and spaced from the right-hand end thereof. If then it is desired to produce the feather edge scarf of Fig. 8^a, the feed roll 11 is tilted, and the guide and presser allowed to resume their 25 right-hand positions, all as shown in Fig. 8. Without going into further detailed explanation 30 of what adjustments may be made, it will be evident that the machine may be instantly adjusted by means of the treadles to produce different kinds of scarfs in any desired order and that scarfs which differ from those illustrated 35 will result if the feed roll 11 is adjusted longitudinally into another position to change the location of the point x with respect to the roll.

Although the invention has been set forth as 40 embodied in a particular machine, it will be understood that the invention is not limited in the scope of its application to the particular machine which has been shown and described.

Having described my invention, what I claim 45 as new and desire to secure by Letters Patent of the United States is:

1. A skiving machine having, in combination, a knife, an angularly adjustable feed roll, an 50 edge guide, a presser, said edge guide and presser being adjustable across the work-supporting surface of the feed roll, stops for limiting the extent of this movement of adjustment, yielding means for normally holding the guide and presser in a position determined by one of the stops, and operator-controlled means for moving them instantly into a position determined by the other stop.

2. A skiving machine having, in combination, a knife, an angularly adjustable feed roll, an 55 edge guide, a presser, said edge guide being adjustable across the work-supporting surface of the feed roll, adjustable stops for limiting the extent of the movement of adjustment, yielding means for normally holding the guide in a position determined by one of the stops, and operator-controlled means for moving it instantly into a position determined by the other stop.

3. A skiving machine having, in combination,

a rotary knife, a feed roll, a support for the roll angularly adjustable to vary the inclination of the scarf produced, a presser for holding the work against the roll, a guide for engaging the edge of the work, a carrier for said presser and guide 5 slidably mounted upon the feed roll support, yielding means for holding the carrier at one limit of its path of sliding movement, and operator-controlled means for adjusting the feed roll support angularly and for moving the carrier 10 instantly into selected positions relative to the roll irrespective of the angular position of the feed roll support.

4. A skiving machine having, in combination, 15 a knife, an edge guide, a presser, a feed roll, said guide and presser being mounted for adjustment across the periphery of the feed roll to vary the width of the scarf produced, yielding means tending at all times to move the guide and presser into and to hold it in a predetermined position 20 at one limit of its path of movement, said feed roll being angularly adjustable to vary the character of the scarf, and two operator-controlled means manipulation of one of which tilts the feed roll, and manipulation of the other of which 25 adjusts the presser and guide instantly to the other limit of its path of movement.

5. A skiving machine having, in combination, 30 a rotary disk knife, an angularly adjustable feed roll, a presser and an edge guide angularly adjustable with the roll and slidably adjustable along the periphery of the roll whereby, with the roll in an angular position in which the upper element of its periphery is parallel or substantially so to the plane of the cut of the knife and 35 the edge guide is above the periphery of the roll and spaced from the end thereof, a comparatively narrow fold scarf will be produced, whereas with said upper element at a considerable angle 40 to the plane of the cut of the knife and with the work engaging-face of the edge guide in substantial alinement with one end of the roll, a wider feather edge scarf will be produced, and operator-controlled means capable of instant 45 manipulation to adjust the parts of the machine into either of these two positions.

6. A skiving machine having in combination, 50 a knife and a feed roll mounted for relative angular adjustment to vary the inclination of the scarf produced, a presser and edge guide mounted for adjustment across the periphery of the feed roll to vary the width of the scarf produced, and two operator-controlled means manipulation of one of which instantly causes relative angular adjustment between the knife and 55 roll and manipulation of the other of which instantly adjusts the presser and guide.

HIOTTE A. DAVIS.
